DOOR FOR TUBULAR FIRE ESCAPES

Filed Oct. 15, 1923

2 Sheets-Sheet 2

Arthur H. Sturges.

UNITED STATES PATENT OFFICE.

ARTHUR H. STURGES, OF OMAHA, NEBRASKA.

DOOR FOR TUBULAR FIRE ESCAPES.

Application filed October 15, 1923. Serial No. 668,704.

To all whom it may concern:

Be it known that I, ARTHUR H. STURGES, a citizen of the United States, residing at Omaha, in the county of Douglas and State 5 of Nebraska, have invented certain new and useful Improvements in Doors for Tubular Fire Escapes, of which the following is a specification.

The present invention relates to fire escapes, and more particularly a door for the outlet or lower ends of tubular fire escapes, of that type which is shown in my co-pending application Serial No. 668,703, filed of even date herewith.

15 An object of the present invention is to provide a closure for the exit or outlet end of the fire escape for the purpose of preventing unauthorized entrance to the lower end of the fire escape and to prevent accumulations of rubbish, snow and the like which are found to accumulate in these devices when their exit ends are open and exposed.

20 A further object of the invention is to provide a closure for the exit end of the fire escape which may be opened from a distant point, such as at the top of the fire escape or where the persons are adapted to enter the same.

Another object of the invention is to provide 30 a device of this character which may be applied to the usual commercial fire escapes without altering the construction of the same, and which embodies features inherent in the attachments for supporting and operating the closure.

35 A still further object of the invention is to provide a fire escape closure of this character, with means for opening it from the entrance to the device, and a supplemental 40 means for causing the opening of the device when a person reaches the lower end thereof, the latter device being supplemental to the first opening means so that should for any reason the first opening means become inoperative through breakage, rusting or the like the second operating means will always be in position to automatically operate as soon as a person or object strikes the lower end of the fire escape. This feature of the invention 45 also embodies the housing or protection of the secondary and primary opening devices to protect them from being tampered with and also from the elements.

With the foregoing and other objects in view, the invention will be more fully de-

scribed hereinafter and will be more particularly pointed out in the claims appended hereto.

In the drawings, wherein like symbols refer to like or corresponding parts throughout the several views,

Figure 1 is a longitudinal section taken through a fire escape having the closure and operating means therefor applied to the fire escape and constructed according to this invention.

Figure 2 is a fragmentary side elevation of the exit end of the fire escape.

Figure 3 is a lower end elevation of the fire escape showing the closure in a closed position.

Figure 4 is a similar view with the closure open.

Figure 5 is an inner end elevation of the lower end section of the fire escape, looking toward the closure in closed position.

Figure 6 is a fragmentary enlarged view of the locking and releasing means for the closure, the view being taken longitudinally through the lower end of the fire escape near the closure.

Figure 7 is a detail enlarged section taken longitudinally through one of the opening devices for one of the doors, and

Figure 8 is a horizontal section taken through the lower end of the fire escape showing the doors closed and showing the secondary releasing means.

Referring to the drawings 10 designates a body portion of a fire escape which may be of tubular construction as illustrated, and which is provided at its upper end with an entrance section 11 adapted to be secured through an opening 12 in the wall 13 of a building, the lower portion or bottom of the entrance portion 11 being substantially flush with the floor 14 of the building. The entrance portion or section 11 may be provided with a hand rail 15 which extends into the entrance section for facilitating the positioning of the person in the upper end of the fire escape.

The lower end of the fire escape 10 is provided with an exit section 16 which may be cylindrical or the like and which is supported upon a base 17 of concrete or other suitable material to support the exit section 16 near the ground or other point at which it is desired to discharge the persons from the building.

The body 10 of the fire escape may be supported against an adjacent wall 18 by hanger brackets 19 or the like, the present illustration of the fire escape being disclosed 5 in the above mentioned copending application, and being shown in the present instance as merely illustrative of the type of fire escape to which the closure and its operating mechanism of this invention may be 10 applied.

The exit section 16 is provided at its outlet end with a channel ring 20 having the channel in its outer side, and which reinforces the edge and provides a door frame to 15 which strap hinges 21 or the like are welded or otherwise suitably secured. These hinge straps 21 are preferably arranged in pairs at opposite sides of the ring 20 and the straps 21 of each pair are vertically spaced 20 apart, and carry a pintle or bolt 22 therethrough upon which are mounted complementary hinge straps 23 which extend across and are welded or otherwise suitably secured to the outer faces of door sections 24 and 25. 25 As shown in Figure 3, the door sections carry the straps 23 across their outer faces, and the lower straps are shorter than the upper ones and carry set screws 26 behind which the lower ends 27 of closing springs 30 30 engage, the springs being carried about the bolt 22 and having their upper ends engaged beneath the straps 21 and in the channel of the ring 20. The springs 28 normally urge the doors 24 and 25 into open position. 35 The door 24 is provided with a lip or extension 29 which is offset outwardly a distance sufficient to overlap and lie closely against the outer face of the door 25.

The doors 24 and 25 are of sheet metal, 40 or the like, and are provided with reinforcing frames 30 disposed upon the inner sides of the doors and to which the locking mechanism is connected. The frames 30 and their panels are substantially semicircular in shape and are adapted to extend 45 across the lower open end of the fire escape and close it. It will be noted from Figure 8 that the frames 30 project into the open end of the section 16 while the panels of the 50 doors lie across the outer edge of the section 16 and also of the reinforcing ring 20.

The frame 30 of one of the doors, preferably the door carrying the overlapping lip 29, is provided upon its lower end and near its outer edge with an inwardly extending lip 31 adapted to support a vertically extending rod 32 which is connected by a flexible chain 33 to its door section 24. The rod 32 extends upwardly along the inner side of 55 the door 24 and is adapted to engage at its upper end upon a cam 34 which is formed upon the lower edge of a hook 35. The hook 35 is pivoted at 36 to the door frame 30 and is provided upon its free end with an 60 upstanding hook or finger 37.

The rod 32 is provided with a cross piece 38 secured to the rod near its lower end and adapted to be struck by the feet of the person sliding down through the tube, should the doors not be opened. A spring 70 39 is carried by the door frame 30 at one end and is connected at its other end to the hook 35 for normally urging the latter downwardly when the hook is released by the removal of the rod 32. The rod 32 is held in 75 place between the lip 31 and the cam 35 by the tension of the spring 39 and the rod may be adjusted to the desired length by the coupling sleeve 63 which is carried by the rod. The rod is therefore only supported at its 80 upper and lower ends and may be easily displaced from beneath the cam 35 to release the latter and disengage the hooks 37 and 51. The chain 33 prevents the loss of the rod 32.

Welded or otherwise suitably secured to the upper side of the outlet section 16 of the fire escape is a box or enclosure 39' having a removable cover 40 which may be locked or otherwise suitably secured upon the open upper side of the box 39'. Within this box 90 is welded or otherwise suitably secured a bracket 41 having an upstanding arm 42 through which is slidably disposed a rod 43. The rod 43 may have a turn buckle 44 thereon on the eye piece 45 of which is connected to 95 a cable 46 which is threaded through a tube or housing 47 secured along the outer side of the fire escape. The forward end of the rod 43 is provided with a washer 48 adjustably held on the rod by lock nuts 49 and which is normally urged outwardly by a spring 50 arranged about the rod 43 and interposed between the washer 48 and the bracket arm 42. At its forward end, the rod 43 is suitably connected to a lever hook 51 which is 100 pivoted at 52 upon the forward end of the bracket 41 and which has a bill 53 which projects downwardly through the bottom of the casing 39' and through the upper wall of the outlet section 16 of the fire escape, the 105 bill 53 engaging the upstanding hook 37 of the lever 35 for locking the doors 24 and 25 closed.

As the door 24 is adapted to be snapped into closed position, the hook lever 51 is 110 limited in its downward movement by an adjustable stop 54 threaded through the front wall of the casing 39' and arranged to engage the upstanding portion of the hook lever. The inner wall of the outlet section 16 may be provided with a shield 55 in the form of a tapered block or member adapted to ward off the head or other parts of the person from contact with the depending end of the hook 53 when the doors are 115 closed.

The tube or pipe 47 extends along the fire escape body 10 to the top thereof and may be secured in place by any suitable fastening devices and is shown in the pres- 120 125 130

ent instance as being welded as at 56 in Figure 1 for holding the pipe in true position over the entrance section 11.

The cable 46, at its upper end is connected 5 to the arm 57 of a lever 58 which is pivotally mounted at 59 upon a frame 60 which is fitted in the opening 12 of the building and upon which the entrance section 11 is supported. This lever 58 is adapted to be 10 drawn inwardly for pulling the cable 46 and releasing the doors. As shown, the opening 12 of the building may be provided with suitable doors 61 arranged to close the entrance opening as is set forth more in 15 detail in the copending application above referred to.

In operation, when it is desired to use the fire escape a person before entering the section 11 thereof pulls the lever 58 inwardly 20 and thus pulls the cable 46 through the pipe 47 and lifts the hook lever 54 out of engagement with the hook or lever 20. As soon as this is done the springs 28 which are incorporated in the door hinges, and enclosed in 25 the metal casings 62, swing the doors 24 and 25 into open position as shown in Figure 4, and in dotted lines in Figure 1.

Should for any reason the cable 46 break or the mechanism become otherwise disarranged or inoperative, and the doors 24 and 25 fail to open when the lever 58 is turned, in order to prevent the device from forming a fire trap, the secondary operating means 32, in the form of a rod, is used. The person sliding through the fire escape 10 enters 35 the outlet section 16 and is impinged against the rod 32 and its cross piece 38. This jars the rod and knocks the lower end thereof from its support or lug 31, or disengages the 40 upper end of the rod from the cam 34. In either event the hook 35 is released and is permitted to drop under tension of the spring 39 so that the springs 28 in the door 45 hinges are free to swing the doors into open position.

As shown in Figures 1 and 5, the sections of the release rod 32 may be provided with a coupling 63 which permits the adjustment of the rod longitudinally so as to fit with a 50 nicety between the supporting finger or bracket 31 and the cam 34 of the hook 35. It is apparent that when the primary operating device fails to operate, the secondary device may be brought into operation so as 55 to insure the releasing and opening of the doors 24 and 25 under all conditions.

When it is desired to close the doors it is only necessary to set the rod 32 upon its support 31 and engage the upper end of the 60 rod with the high point of the cam 34. The doors 24 and 25 may now be swung closed with the lip 29 overlapping the door section without the locking device so as to insure the securement of the doors in closed position by the one locking device.

When the rod 32 is knocked off of its support 31 and from beneath the cam 34, the chain 33 prevents loss of the rod and suspends the same in such position that the rod may be easily grasped and readjusted. 70 The cable 46 and tube 47 permit the operation of the primary releasing device from a distant point, such as at the entrance opening to the fire escape, so that the person upon entering the fire escape may first 75 open the exit doors.

It will also be noted that all of the parts are housed either behind the doors 24 and 25 or in the casing 39' so that rain, dust, moisture and the like cannot gain access to 80 the working parts. The pipe 47 is sealed in the end of the casing 39' and is also sealed at its other end in the casing 64 which may be a frame work or the like arranged in the wall opening 12 and at the top of the entrance section.

I do not wish to be restricted to the size, form, and proportions of the various parts, and obviously changes could be made in the construction herein described without departing from the spirit of the invention, it 90 being only necessary that such changes fall within the scope of the appended claims.

What is claimed is:—

1. In combination with a tubular fire escape, a pair of doors hinged upon the exit end of the fire escape for closing said end, means connected to the doors for normally urging the same to spring into an open position, a hook carried by one of the doors, a 95 hook mounted on the fire escape, a spring normally interlocking said hooks for holding the doors closed, a cable connected to said second hook and extending along the fire escape to the entrance end thereof and a lever pivoted upon the entrance end of the fire escape and connected to said cable for drawing the same when the lever is 100 swung whereby said doors may be released to swing into an open position upon the 105 operation of said lever.

2. The combination with a tubular fire escape, a pair of doors hinged upon the exit end of the fire escape, springs connected to the doors for normally urging the same into 115 open position, a hook on one door, an overlapping lip on said door arranged to engage the other door when both of said doors are closed, a hook lever pivoted upon the outlet end of the fire escape and arranged 120 to interlock with the hook upon the door for holding the doors closed, a rod slidably mounted on the fire escape having one end connected to said hook lever, a spring connected to the rod for urging it to move outwardly whereby to maintain the hook lever in engagement with said hook, a cable connected to said rod, and a lever mounted upon the entrance end of the fire escape and 125 connected to said cable, said lever being 130

- adapted to be swung for drawing said cable and pulling said rod against the tension of the spring to release the hook lever from said hook.
3. The combination with a tubular fire escape, a pair of doors hinged upon the exit end of the fire escape, springs connected to said doors for swinging the same into open position, a lip on one door adapted to overlap the other door when both doors are closed, a hook on the door having the lip, a hook lever pivoted upon the fire escape, a spring operatively connected with the hook lever for normally urging it into engagement with the hook, and releasing means connected to the hook lever and extending to the entrance end of the fire escape for releasing the hook lever from the hook and permitting said doors to open.
- 10 4. The combination with a tubular fire escape, a pair of doors for closing the exit end of the fire escape and normally urged into open position, a locking member carried by the fire escape, a second locking member carried by the doors, said locking members being adapted to interlock for holding the doors closed, primary releasing means connected to one of said members and extending along the fire escape to the entrance end thereof and operable from said

entrance end to release the doors, and a secondary releasing means carried by the doors and connected to the adjacent locking member for operation upon failure upon said first releasing means.

5. The combination with a tubular fire escape, a pair of doors hinged upon the exit end of the fire escape and normally urged into open position, a locking member carried by the doors, a second locking member carried by the fire escape, a casing enclosing the second locking member, a rod slidably mounted in the casing connected to said locking member, a spring connected to the rod for urging it to move in one direction, a cable connected to the rod for drawing it in the other direction, a pipe enclosing the cable and extending lengthwise of the fire escape to the entrance end thereof, and a lever pivotally mounted at the entrance end of the fire escape and connected to said cable for drawing the same when the lever is swung and releasing said locking members one from the other.

In testimony whereof, I have affixed my signature in presence of two witnesses.

ARTHUR H. STURGES.
